CLAIM

The ornamental design for a cervical neck pillow as shown and described.

DESCRIPTION

FIG. 1 is a perspective view of cervical neck pillow showing my new design;

FIG. 2 is another perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The equal-length broken lines depict portions of the cervical neck pillow that form no part of the claimed design.
